UNITED STATES PATENT OFFICE.

JANE GRAY STOKES, OF LARCHMONT, NEW YORK.

DESIGN FOR A DOLL SHOE.

Application filed January 5, 1926. Serial No. 15,950. Term of patent 7 years.

To all whom it may concern:

Be it known that I, JANE GRAY STOKES, a citizen of the United States, residing in Larchmont, in the county of Westchester and State of New York, have invented a certain new, original, and ornamental Design for Doll Shoes, of which the following is a specification, reference being had to the accompanying drawings, of which—

I claim:

The ornamental design for a doll shoe as shown.

JANE GRAY STOKES.
